CLAIM

The ornamental design for a folding axe, as shown and described.

DESCRIPTION

FIG. 1 is a perspective view of the folding axe showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof when the axe is folded;

FIG. 10 is an enlarged view of a portion indicated with numeric 10 in FIG. 1; and,

FIG. 11 is an enlarged view of a portion indicated with numeric 11 in FIG. 2.

The dash-dash broken lines in the drawings depict portions of the folding axe that form no part of the claimed design. The dash-dot-dash lines in FIGS. 1, 2 10 and 11 depicting the areas of enlargement form no part of the claimed design.
